WIRELESS LIGHTING FIXTURE

Curtiss M. Peasley, 25 Boulder Drive,
Burlington, Mass. 01803

Filed May 21, 1971, Ser. No. 145,990

Term of patent 14 years

Int. Cl. D26—05

U.S. Cl. D48—24

Fig. 1.

Fig. 2.

Fig. 3.

Fig. 4.

FIG. 1 is a perspective view of a wireless lighting fixture showing my new design;

FIG. 2 is a rear perspective view thereof;

FIG. 3 is a front elevational view thereof.

FIG. 4 is a top plan view thereof.

The chain is broken away in FIGS. 1, 2 and 3 to indicate indeterminate length.

I claim:

The ornamental design for a wireless lighting fixture, substantially as shown and described.
